UNITED STATES PATENT OFFICE.

OSBORNE E. SULLY, OF SPENCER, IOWA.

DESIGN FOR A DISPLAY-RACK.

SPECIFICATION forming part of Design No. 27,014, dated May 4, 1897.

Application filed March 20, 1897. Serial No. 628,533. Term of patent 7 years.

To all whom it may concern:

Be it known that I, OSBORNE E. SULLY, a citizen of the United States, residing at Spencer, in the county of Clay and State of Iowa, have invented and produced a new and original Design for a Display-Rack, of which the following is a specification, reference being had to the accompanying drawing, forming a part thereof, which represents a perspective view of a rack constructed in accordance with my design.

Standards A are placed in parallel order and are connected at the top. A bow B appears as supported by the upper portion of the standards. The base of the device is formed of rods C, crossed in the form of an

X, being in a horizontal plane and at a right angle to the standards A. A vertically-disposed arch D is supported by the outer ends of the crossed rods C, and at each side of the arch and the crossed rods a horizontal skeleton wing E is formed, which not only connects with the arch, but also with the standards A.

I claim—

The design for a display-rack herein shown and described.

OSBORNE E. SULLY.
